UNITED STATES PATENT OFFICE.

THOMAS J. HAYES, OF ROSLINDALE, MASSACHUSETTS, ASSIGNOR TO ARBETTER FELLING MACHINE COMPANY, OF BOSTON, MASSACHUSETTS, A CORPORATION OF MAINE.

FEEDING MECHANISM FOR SEWING-MACHINES.

1,388,183.

Specification of Letters Patent. Patented Aug. 23, 1921.

Application filed January 4, 1917. Serial No. 140,522.

To all whom it may concern:

Be it known that I, THOMAS J. HAYES, a citizen of the United States, and resident of Roslindale, county of Suffolk, State of Massachusetts, have invented an Improvement in Feeding Mechanism for Sewing-Machines, of which the following description, in connection with the accompanying drawing, is a specification, like characters on the 10 drawing representing like parts.

This invention relates to improvements in feeding mechanisms for sewing machines and the general object thereof is to provide a novel feed dog actuating mechanism which 15 will be simple in construction and effective in operation and in which the feeding mechanism will be capable of movement toward and from the stitch forming mechanism.

This is accomplished in the preferred construction illustrated herein by mounting the feed dog upon one or preferably two rock shafts which are supported at the opposite end in pivotally mounted journals so that the feed dog and its actuating mechanism 20 25 may be moved in an arc toward and from the stitch forming mechanism.

More particularly the object of the invention is to provide a feeding mechanism for sewing machines having special accessories 30 coöoperating with the stitch forming mechanism, such as bender mechanisms, looper mechanisms and the like, the feeding mechanism being so constructed as to provide ample room for said accessories and their actuating mechanisms.

Another feature of the invention consists in providing a head containing a single vertical shaft, journaled in the usual standard of a blind stitch sewing machine, for actuating the bender shaft and bender and also a rock shaft which serves to impart up and down work engaging and releasing movements to the feed dog so that the proper timing of the bender and feed dog will be maintained.

Another feature of the invention consists in utilizing one or more hollow rock shafts for actuating the feeding mechanism and providing said rock shafts with lubricant 50 reservoirs within the bearings in which they are journaled.

Other features of the invention will more fully appear from the following description

and accompanying drawings and will be particularly indicated in the annexed claims. 55

In the drawings;

Figure 1 is a side elevation of a blind stitch sewing machine of the Arbetter type, a portion of the bed plate and standard being shown in section, 60

Fig. 2 is a bottom plan view of the sewing machine illustrated in Fig. 1 showing the feeding mechanism and illustrating the mechanism for driving the bender shaft, the latter being broken away, 65

Fig. 3 is a front end elevation of the sewing machine illustrated in Fig. 1,

Fig. 4 is a rear end elevation, the standard being shown in vertical section,

Fig. 5 is an enlarged detail view of the 70 work support, the feed dog and the means for actuating the same,

Fig. 6 is a detail vertical sectional view of one of the rock shafts for actuating the feed dog and of the bearings forming a part 75 of the work support in which it is journaled.

Fig. 7 is a detail plan view of the feed dog.

The sewing machine which embodies the present invention may be of the type illustrated in my prior application Ser. No. 108,279, filed July 10, 1916 and which is addressed to a bender mechanism, the present feeding mechanism being designed to be used with the bender mechanism disclosed in that application. 85

The sewing machine illustrated herein is of the "Arbetter" type having a bed plate 1 preferably provided with an upwardly projecting boss 2 forming a base for a standard 3 which carries the usual overhanging arm 4, 90 terminating in a head 5 which supports a curved oscillating needle and complementary stitch forming mechanism. A main shaft 6 is journaled in suitable bearings in the arm and standard, the bearing in the standard 95 preferably comprising a boss 8 having a bushing 9 surrounding the shaft.

The main shaft 6 is rotated by a pulley 10 having a hand wheel 11 which may be connected with the shaft in the usual manner 100 but preferably is provided with a novel connection hereinafter to be described.

The shaft 6 is provided at its opposite end with suitable means for actuating the needle and complementary stitch forming mechanism which may be of any desired type but 105

preferably is similar to that disclosed in my prior application aforesaid.

The head of the machine is provided with a depending hook bracket 12 to which a 5 presser foot 13 is secured. The feeding mechanism is adapted to coöperate with the presser foot and preferably is carried by a work supporting member which is yieldably and adjustably supported by said bed plate 10 in coöperative relation to the presser foot.

As illustrated herein the work supporting member is in the form of a centrally recessed block 14 which extends through the bed plate 1 and desirably is provided 15 with a removable cap 15 slotted to accommodate the rows of teeth of the feed dog.

The work supporting member 14 is provided at its ends with extensions 16, 17, 18 and 19 terminating respectively in bosses 20, 21, 22 and 23 which form journals for 25 the ends of the rock shafts which serve to operate the feed dog, as will hereinafter more fully appear. The work supporting member is also provided with projecting members 24, 25 and 26 which extend toward the end of the machine, the members 24 and 26 having secured thereto downwardly depending arcuate guides 27, 28 which are provided with longitudinal slots 29 (see 30 Fig. 1). The guides 27 and 28 slidably engage the outer walls 30, 31 of a bracket 32 which is secured to and depends from the under surface of the bed plate. This bracket is provided at its lower end with a 35 transverse web 33 having a central screw threaded aperture in which a screw 34 having a hollow stem is seated.

A helical spring 35 mounted at its lower end upon the upper end of the screw 34 enclosing a guiding rod 36 engages at its upper end the extension 25 of the work supporting member and normally maintains the work support in engagement with the presser foot 13. By the adjustment of the 45 screw 34 the pressure of the work support against the presser foot may be regulated in the well known manner.

The guides 27, 28 may conveniently be secured in proper relation to the outer walls 50 30, 31 of the bracket by bolts 37 anchored in the walls 30, 31 of the bracket and extending through the slots 29 in the arcuate guides 27, 28, suitable washers 38 overlying said slots to permit sliding movement 55 between the guides and the walls of the bracket.

The feed dog 39 preferably is of rectangular form and is provided with a plurality of serrated work engaging members adapted 60 to extend through the usual slots in the upper surface of the work supporting cap 15. The dog 39 is provided with downward and lateral extensions 40, 41 which are secured by screws 42, 43 to portions 44, 45 of a 65 feed bar which has a central portion 46 off-

set to provide room for the bender and its operating mechanism.

The feed dog and feed bar as thus constructed form in effect an integral structure which hereinafter will be referred to generally as the feed dog.

The end portions 44, 45 are connected respectively to mechanisms adapted respectively to give the feed bar and feed dog an up and down work engaging and releasing movement and an advancing and retracting movement. The mechanism for producing these movements, illustrated in the preferred form of the invention disclosed herein, comprises rock shafts 47, 48 which preferably are tubular in form and are provided with arms connected to the ends of said feed bar and operated by suitable mechanisms hereinafter to be described.

The rock shaft 47 which is adapted to 85 impart up and down or work engaging and releasing movement to the feed dog is journaled in bearings 20, 21 in the extensions of the work supporting member and is provided with an arm 49 having a stud 50 carrying a cross head 51 mounted in a slot 52 in the portion 44 of the feed bar. The shaft 47 is mounted at its opposite end in a bearing 53 which is provided with an upwardly extending ear 54 pivotally mounted upon a 95 shaft 55 which is supported by the bed plate of the machine preferably within and slightly above the plane of the lower surface of said bed plate.

The rock shaft 47 has an arm 56 which 100 is connected by a link 57 preferably made in two sections conveniently to embrace a ball-stud 58 which is eccentrically mounted upon the face of the spiral gear 59 carried at the bottom of a vertical shaft 60 which is journaled in suitable bearings in the standard of the machine and is provided at its upper end with a beveled gear 61 which meshes with a driving gear 62 fast upon the main shaft 6.

The opposite end 45 of the feed bar is pivotally mounted on a stud 63 extending laterally from an arm 64 upon the rock shaft 48. The rock shaft 48 is journaled at its outer end in the bearings 22, 23 of the work 115 supporting member and is journaled at its opposite end in a bearing 65 which, like the bearing 53, is provided with an upwardly extending ear 66 pivotally mounted upon the transverse shaft 55. The rock shaft 48 is also provided with an arm 67 which is oscillated by a link 68 through suitable mechanism.

A preferred means for oscillating the arm 67 comprises a lever 69 fulcrumed upon a 125 stud 70 which projects from the end of a link 71 which is provided at its opposite end with a boss 72 which is pivotally mounted upon a stud 73 in the end of one arm 74 of a bell crank lever which is pivotally mounted 130

upon a stud 75 extending into the wall of the standard. The other arm 76 of the bell crank lever is provided with a screw 77 which extends through a slot in the side of said standard and is provided with a head 78 adapted to engage an arcuate surface 79 upon the side of the standard. The lower end of the link 69 is pivotally connected to a stud 80 upon the end of an arm 81 of a bell crank lever which is pivotally mounted upon a stud 82 projecting laterally from a bracket 83 depending from the under surface of the bed plate. The other arm 84 of said bell crank carries a ball-stud 85 to which the end of the link 68 is pivotally connected.

At its upper end the lever 69 is bifurcated to form parallel arms 86, 87 which engage a cam 88 secured upon the main shaft within the standard.

20 By reason of the construction aforesaid the rotation of the cam oscillates the forked end of the standard about its fulcrum 70. This fulcrum however being upon the end of a link 71 in turn oscillates about its pivotal stud 73 which projects from the end of the arm 74 of the bell crank. By adjusting the bell crank in the manner above described the stud 73 may be caused to approach more or less closely to the axis of the lever 69. When 25 the stud 73 is in the plane of the axis of the lever, the fulcrum 70 of the lever will oscillate equally upon either side of the plane of the axis of the lever but when the stud 73 is moved to the side of the plane of the 30 axis of the lever 67 a longitudinal movement will be imparted to the lever by reason of the arcuate movement of the fulcrum 70 at the end of the link 71. The longitudinal movement of the lever 69 serves to oscillate 35 the arm 81 of the bell crank lever the other arm 84 of which is connected by the link 68 to the arm 67 of the rock shaft 48. This construction affords a very accurate and sensitive adjustment for regulating the amplitude 40 of oscillation of the rock shaft 48 and consequently the extent of movement of the feed dog.

The feed bar and feed dog are carried directly upon the arms of the rock shafts and 45 the rock shafts in turn are supported at their outer ends in the bearings in the extension of the work supporting member so that the work supporting member and the feed dog are movable in unison toward and from the 50 stitch forming mechanism, consequently a proper relation between them is at all times maintained and their proper co-operation in presenting the work to the stitch forming mechanism insured.

60 By reason of the fact that the universally pivoted links 57 and 68 are of a constant length and their ends which engage respectively the arms 56 and 67 of the rock shafts 47 and 48 adapted to swing in the arc of the 65 circle, the depression of the work support by

engagement with thicker material will cause a slight rocking movement of the shafts 47 and 48 which will thrust the feed dog slightly farther through the work plate and advantageously force it a little deeper into 70 thicker goods.

While in the preferred embodiment of the invention disclosed herein the work support carries the ends of both shafts for actuating the feed dog it will be obvious that a single 75 rock shaft may be used for imparting one of the movements of the feed dog while other mechanism usual in the art may be employed for imparting the other necessary movement to said dog.

In order further to maintain the proper coordination between the elements of the work presenting mechanism means are provided whereby the bender is actuated from the same shaft as that which causes the up and down work engaging and releasing movement of the feed dog. This is very important since the timing of the reciprocation of the bender relatively to the feed dog must be accurate in order that the bender may be 80 withdrawn from the work out of the path of the feed dog to avoid interference with the advancing movement of said dog.

This is accomplished in the preferred embodiment of the invention shown herein 95 by actuating the bender mechanism from a shaft 89 suitably journaled in the bearings depending from the under surface of the bed plate and provided with a spiral gear 90 which engages a spiral gear 59 upon the vertical shaft 60.

As a result of the construction described the work support and feed dog and also the bender oscillate about pivots located beneath the standard of the machine, the radius of 105 oscillation being of sufficient length to cause the work support and its feed dog and the bender to move substantially vertically.

Any suitable means may be provided for depressing the work support to permit the 110 insertion and removal of the work. In the preferred construction illustrated herein a flexible connection such as a cord or chain 92 is secured to the projection 25 upon the work supporting member and is carried beneath a pulley 93 suitably journaled in bosses 94 projecting laterally from the standard 32, the opposite end of said cord being connected to an arm 95 of a shaft 96 which is journaled in suitable bosses 97, 98 120 depending from the bed plate and is operated by an arm 99 which is connected to the usual knee lever.

A further feature of the invention consists in utilizing a portion of the hollow interior 125 of the end of each rock shaft as a reservoir for lubricant for the inclosing bearings. This construction is illustrated in Fig. 6 in which the hollow rock shaft 47 is shown as journaled in the bearings 20, 21, the feed 130

dog engaging arm 49 being interposed between the bearings 20 and 21. A partition, which may be a plug 100, is inserted in the tubular rock shaft just beyond the end of the bearing 20 and the other end of the hollow rock shaft 47 is closed up by a plug 101 screwed into the end of the rock shaft. The plug 101 desirably is provided with a central oil duct 102 through which the lubricant may be introduced into the reservoir 103 thus formed. Ducts 104 and 105 lead respectively from the reservoir to the bearings 20 and 21. The reservoir thus constructed is of sufficient capacity to contain enough lubricant to supply the bearings for a considerable period of time so that the usual necessity of frequently oiling the bearings is obviated. Furthermore both ends of each of the shafts which are thus equipped are exposed so that the reservoirs can easily be replenished.

In the operation of sewing machines it is often desirable to disconnect the pulley from its operative relation to the main shaft in order to provide for the winding of the bobbins and for other purposes. It is also desirable to provide means for adjusting the main shaft longitudinally to take up wear between the bearings and the mechanisms which actuate the stitch forming mechanism and the feeding mechanism, such for example as that which may occur between the hub of the gear 62 and the end of the bushing 9. This is accomplished in the mechanism illustrated herein by mounting the pulley 10 upon a sleeve which abuts against the end of the boss 8 and through which the shaft 6 is longitudinally adjustable.

As illustrated in the accompanying drawings a sleeve 106 is provided with a flange 107 which abuts against the end of the boss 8 and its bushing 9, the outer end of the sleeve extending a short distance beyond the end of the shaft 6.

A screw 108 seated in the end of the shaft 6 is provided with an enlarged head 109 which engages the end of the sleeve 106. The sleeve 106 is secured to the shaft by a set screw 110 which projects into a slot 111 extending longitudinally of the shaft. By adjusting the screw 108, therefore, the shaft 6 will be moved longitudinally of its bearings to take up wear on the bushing. This construction also obviates the necessity of careful machining of certain of the parts and thus aids in assembling.

The pulley 10 is rotatably mounted upon the sleeve 106 and a nut 112 provided with a milled hand grip 113 screwed upon the end of the sleeve serves to clamp the hub of the pulley 10 against the flange 107 when it is desired to actuate the main shaft. When the nut 112 is backed off the pulley 10 is released and rotates freely upon the sleeve 106 and may be used for winding bobbins, etc.,

without actuating the machine. The nut 112 is held from coming off by contacting with the inner face of the enlarged head 109 of the screw 108.

Another novel feature of the sewing machine illustrated herein comprises mechanism for regulating the take up. The take up arm 114 is provided at its end with a boss 115 transversely apertured to receive a sliding bar or shaft 116 which is secured to a stud 117 projecting from an arm 118 which desirably is connected to and rotates about the axis of the main shaft. The boss 115 is provided with a laterally extending stud 119 which is eccentrically seated in a bushing 120 which is rotarily adjustable in the sewing machine head, the axis of said bushing preferably being upon the same horizontal plane as the axis of the main driving shaft.

In operation the rotary movement of the stud 117 oscillates and reciprocates the slide bar 116 and thereby imparts an oscillatory movement to the take-up arm 114 about the center of the stud 119. By rotarily adjusting the bushing 120 the axis of the stud 119 may be moved toward and from the axis of the main driving shaft thereby increasing or decreasing the distance between the axes of the studs 117 and 119 and consequently varying the extent of movement of the take up arm. This adjustment also regulates its timing relatively to the hook as the axis of the stud is raised or lowered relatively to the horizontal plane of the axis of the main shaft.

It will be understood that the particular mechanism disclosed herein is of an illustrative character and that various modifications may be made within the spirit and scope of the following claims.

Having thus described my invention, what I claim as new and desire to secure by Letters Patent is:

1. In a sewing machine comprising a stationary bed plate, an overhanging arm and stitch forming mechanism carried thereby, feeding mechanism including a pair of rock shafts, means for yieldably supporting the same at one end relatively to the stitch forming mechanism and said bed plate, means for pivotally supporting said shafts at the opposite end, a feed dog operating through an aperture in said bed plate, means for supporting said feed dog from said rock shafts and means for oscillating said rock shafts to actuate said feed dog.

2. In a sewing machine comprising a bed plate, an overhanging arm and stitch forming mechanism carried thereby, feeding mechanism including a rock shaft pivotally mounted at one end and movable at its opposite end relatively to said bed plate, means for oscillating said rock shaft, a feed dog operating through an aperture in said bed plate, means connecting said feed dog to

said rock shaft to cause the oscillation of the rock shaft to advance and retract said feed dog and means for imparting an up and down work engaging and releasing movement to said feed dog.

3. In a sewing machine comprising a bed plate, an overhanging arm and stitch forming mechanism carried thereby, feeding mechanism including a rock shaft pivotally mounted at one end and movable at its opposite end relatively to said bed plate, means for oscillating said rock shaft, a feed dog operating through an aperture in said bed plate, means connecting said feed dog to said rock shaft to cause the oscillation of the rock shaft to advance and retract said feed dog and means for adjusting the amplitude of movement of said feed dog.

4. In a sewing machine comprising a bed plate, an overhanging arm and stitch forming mechanism carried thereby, feeding mechanism including a rock shaft pivotally mounted at one end and movable at its opposite end relatively to said bed plate, means for oscillating said rock shaft, a feed dog operating through an aperture in said bed plate, means connecting said feed dog to said rock shaft to cause the oscillation of the rock shaft to impart an up and down work engaging and releasing movement to said feed dog and means for advancing and retracting said feed dog.

5. In a sewing machine comprising a bed plate, an overhanging arm and stitch forming mechanism carried thereby, a work supporting member, means for yieldably supporting the same from said bed plate, a rock shaft, means for supporting one end of the same in said work supporting member, means for pivotally supporting the opposite end of said rock shaft, a feed dog reciprocably mounted in said work supporting member, means operable by the oscillation of said rock shaft to advance and retract said feed dog and means for imparting an up and down work engaging and releasing movement to said feed dog.

6. In a sewing machine comprising a bed plate, an overhanging arm and stitch forming mechanism carried thereby, a work supporting member, means for yieldably supporting the same from said bed plate, a rock shaft, means for supporting one end of the same in said work supporting member, means for pivotally supporting the opposite end of said rock shaft, a feed dog reciprocably mounted in said work supporting member, means operable by the oscillation of said rock shaft to impart up and down work engaging and releasing movement to said feed dog and means for advancing and retracting said feed dog.

7. In a blind stitch sewing machine comprising a stationary bed plate, a curved oscillating needle, complementary stitch forming

mechanism and a presser foot located above said bed plate, a work supporting member, and means for supporting the same in co-operative relation to said presser foot; parallel rock shafts journaled at one end in 70

said work supporting member, means for pivotally supporting the opposite end of said rock shafts to permit movement of said work supporting member relatively to said bed plate, a feed dog operating through an 75 aperture in said bed plate, means connecting the respective ends of the feed dog to said rock shafts whereby the oscillation of one rock shaft will impart up and down cloth engaging and releasing movement to said 80 feed dog and the oscillation of the other rock shaft will advance and retract said dog.

8. In a blind stitch sewing machine comprising a stationary bed plate, a standard having an overhanging arm, a curved oscillating needle, complementary stitch forming mechanism and a presser foot carried by said arm, a work supporting member, means for yieldably supporting the same in co-operative relation to said presser foot; parallel 90 rock shafts journaled at one end in said work supporting member, journals for the opposite ends of said rock shafts pivotally mounted upon a shaft extending transversely across the bed plate beneath the 95 standard whereby said work supporting member is movable relatively to said bed plate and said presser foot, a feed dog operating through an aperture in said bed plate, means connecting one of said rock shafts to 100 said feed dog to cause the oscillation of the rock shaft to impart up and down cloth engaging and releasing movements to said feed dog and means connecting the other rock shaft to said feed dog to cause the oscillation of the latter to advance and retract 105 said feed dog.

9. In a blind stitch sewing machine comprising a bed plate, a standard rising therefrom, an arm having a head, a main shaft 110 journaled in said arm and head, a curved oscillating needle, complementary stitch forming mechanism and a presser foot carried by said head; a bracket depending from said bed plate, a work supporting member having depending guides slidably mounted upon said bracket and provided with laterally extending journals, yieldable means on said bracket supporting said work supporting member, rock shafts mounted at one end 115 in said journals, journals for the opposite ends of said shaft pivotally mounted in said bed plate beneath said standard, a feed dog carried by said shafts and means for causing the oscillation of one of said rock shafts 120 to impart up and down cloth engaging and releasing movements to said dog and the oscillation of the other rock shaft to advance and retract said dog.

10. In a blind stitch sewing machine com- 130

6

prising a bed plate, a standard rising therefrom, an arm having a head, a main shaft journaled in said arm and head, a curved oscillating needle, complementary stitch forming mechanism and a presser foot carried by said head, a bracket depending from said bed plate, a work supporting member having depending guides slidably mounted upon said bracket and provided with laterally extending journals, yieldable means on said bracket supporting said work supporting member, rock shafts mounted at one end in said journals, journals for the opposite ends of said shaft pivotally mounted in said bed plate beneath said standard, a feed dog, an arm on one of said rock shafts slidably connected to one end of said feed dog, an arm upon the other rock shaft pivotally connected to the opposite end of said feed dog and means for oscillating said rock shafts whereby the oscillation of the first mentioned rock shaft will impart up and down cloth engaging and releasing movements to said feed dog and the oscillation of the other rock shaft will advance and retract said dog.

11. In a blind stitch sewing machine comprising a bed plate, a standard rising therefrom, an arm extending from the said standard over said bed plate and having a head carrying a curved oscillating needle and complementary stitch forming mechanism, a main shaft journaled in said arm and head and operatively connected to said stitch forming mechanism, a vertical shaft journaled in said standard, means for rotating the same from the main shaft, feeding mechanism including a rock shaft located beneath said bed plate, adapted when oscillated to impart up and down cloth engaging and releasing movements to said feed dog, means for advancing and retracting said feed dog, a bender actuating shaft located beneath said bed plate and means operable from said vertical shaft respectively to oscillate said rock shaft and to rotate said bender actuating shaft whereby the timing of the movements of the bender and feeding mechanism is accurately maintained.

12. In a blind stitch sewing machine comprising a bed plate, a standard rising therefrom, an arm extending from the said standard over said bed plate and having a head carrying a curved oscillating needle and complementary stitch forming mechanism, a main shaft journaled in said arm and head and operatively connected to said stitch forming mechanism, a vertical shaft journaled in said standard, means for rotating the same from the main shaft, feeding mechanism including a rock shaft located beneath said bed plate, adapted when oscillated to impart up and down cloth engaging and releasing movements to said feed dog, a bender actuating shaft located be-

neath said bed plate and means operable from said vertical shaft respectively to oscillate said rock shaft and to rotate said bender actuating shaft whereby the timing of the movements of the bender and feeding mechanism is accurately maintained, a second rock shaft located beneath said bed plate, means for actuating the same and means for causing the oscillation of said second rock shaft to advance and retract said dog.

13. In a blind stitch sewing machine comprising a bed plate, a standard rising therefrom, an arm extending from the said standard over said bed plate and having a head carrying a curved oscillating needle and complementary stitch forming mechanism, a main shaft journaled in said arm and head and operatively connected to said stitch forming mechanism, a vertical shaft journaled in said standard, means for rotating the same from the main shaft, feeding mechanism including a rock shaft located beneath said bed plate, means for causing the oscillation of the same to impart up and down cloth engaging and releasing movements to said feed dog, a bender actuating shaft located beneath said bed plate and means operable from said vertical shaft respectively to oscillate said rock shaft and to rotate said bender actuating shaft whereby the timing of the movements of the bender and feeding mechanism is accurately maintained, a second rock shaft located beneath said bed plate and connected to said feed dog to cause the oscillation of said rock shaft to advance and retract said dog, means for actuating said rock shaft comprising a floating lever located in said standard and having a fork engaging a cam upon the main shaft, means for supporting the fulcrum of said lever adjustably toward and from the longitudinal axis of said lever whereby the amplitude of advancing and retracting movement of the feed dog may be regulated.

14. In a blind stitch sewing machine comprising a bed plate, a standard rising therefrom, an arm having a head carrying a curved oscillating needle and complementary stitch forming mechanism, a main shaft journaled in said arm and head and operatively connected to said stitch forming mechanism, a vertical shaft mounted in said standard, means for rotating the same from the main shaft, feeding mechanism, rock shafts respectively operable to impart up and down work engaging and releasing movements to said feed dog and to advance and retract the same and a bender actuating shaft located beneath said bed plate, a gear having an eccentric stud upon said vertical shaft, a companion gear upon said bender shaft meshing therewith, a link connecting said stud to an arm on the rock shaft operable to impart work engaging and releasing

movement to said dog and means for oscillating the rock shaft which is operable to advance and retract said dog.

15. In a blind stitch sewing machine comprising a bed plate, a standard rising therefrom, an arm having a head carrying a curved oscillating needle and complementary stitch forming mechanism, a main shaft journaled in said arm and head and operatively connected to said stitch forming mechanism, a vertical shaft mounted in said standard, means for rotating the same from the main shaft, feeding mechanism, rock shafts respectively operable to impart up and down work engaging and releasing movements to said feed dog and to advance and retract the same and a bender actuating shaft located beneath said bed plate, a gear having an eccentric stud upon said vertical shaft, a companion gear upon said bender shaft meshing therewith, a link connecting said stud to an arm on the rock shaft operable to impart work engaging and releasing movement to said dog and means for oscillating the rock shaft which is operable to advance and retract said dog comprising an eccentric on the main shaft and a floating lever having a yoke embracing said eccentric and connected at its opposite end to an arm on said rock shaft and means for adjusting the movement of the fulcrum of said floating lever to control the extent of oscillation thereof.

16. In a sewing machine comprising a bed plate, an overhanging arm and head, a presser foot, a curved oscillating needle and complementary stitch forming mechanism carried by said head, a work supporting member extending through an aperture in

said bed plate in coöperative relation to said presser foot, a bracket depending from said bed plate, guides upon said work supporting member engaging ways upon said bracket, means for yieldably supporting said work supporting member from said bracket, rock shafts journaled at one end in said work supporting member means pivotally supporting the other ends of said rock shafts, a feed dog connected to and carried by said rock shafts, and means for oscillating said rock shafts to impart, up and down, forward and back, work engaging and releasing movements to said feed dog.

17. In a sewing machine comprising a bed plate, an overhanging arm and head, a presser foot, a curved oscillating needle and complementary stitch forming mechanism carried by said head, a work supporting member extending through an aperture in said bed plate in coöperative relation to said presser foot, a bracket depending from said bed plate, a helical spring adjustably supported by said bracket engaging said work supporting member, guides upon said work supporting member engaging ways upon said bracket, rock shafts journaled at one end in said work supporting member, means pivotally supporting the other ends of said rock shafts, a feed dog connected to and carried by said rock shafts, and means for oscillating said rock shafts to impart, up and down, forward and back, work engaging and releasing movements to said feed dog.

In testimony whereof, I have signed my name to this specification.

THOMAS J. HAYES.
